DISPENSER TOP FOR A PRESSURE CAN

Robert Henry Abplanalp, Bronxville, and Victor Koenigsberg, Franklin Square, N.Y.; said Abplanalp assignor to Precision Valve Corporation, Yonkers, N.Y., a corporation of New York; said Koenigsberg assignor to Colgate-Palmolive Company, New York, N.Y., a corporation of Delaware

Filed Mar. 7, 1963, Ser. No. 73,867

Term of patent 14 years

(Cl. D9—275)

Fig 4

Fig 5

Fig 6

FIG. 1 is a top perspective view of a dispenser top for a pressure can, showing our new design;

FIG. 2 is a top plan view;

FIG. 3 is a top perspective view from the side opposite that in FIG. 1;

FIG. 4 is an elevational view taken from the bottom of FIG. 2;

FIG. 5 is an elevational view taken from the left of FIG. 2; and

FIG. 6 is an elevational view taken from the right of FIG. 2.

We claim:

The ornamental design for a dispenser top for a pressure can, as shown.
